(57) **CLAIM**

We claim the ornamental design for an electrical connector for connecting with an electrical device, as shown and described.

DESCRIPTION

FIG. 1 is a top perspective view of an electrical connector for connecting with an electrical device.

FIG. 2 is a front elevational view of the electrical connector for connecting with an electrical device depicted in FIG. 1. FIG. 3 is a rear elevational view of the electrical connector for connecting with an electrical device depicted in FIG. 1. FIG. 4 is a right side elevational view of the electrical connector for connecting with an electrical device depicted in FIG. 1.

FIG. 5 is a left side elevational view of the electrical connector for connecting with an electrical device depicted in FIG. 1.

FIG. 6 is a top plan view of the electrical connector for connecting with an electrical device depicted in FIG. 1; and, FIG. 7 is a bottom plan view of the electrical connector for connecting with an electrical device depicted in FIG. 1.

The wavy line at the end of the cable represents a symbolic break in length. The appearance of any portion of the article beyond the break line forms no part of the claimed design. The broken lines in the drawings illustrate portions of the electrical connector for connecting with an electrical device that form no part of the claimed design.

1 Claim, 6 Drawing Sheets
